INVENTOR

BY Victor J. Evans

ATTORNEY

WITNESS:

Geo. Hayes

UNITED STATES PATENT OFFICE.

ALFRED C. HINDS, OF SAN FRANCISCO, CALIFORNIA.

RECEPTACLE.

Application filed February 25, 1925. Serial No. 11,575.

This invention relates to receptacles for containing spices, powders, salt or other granular materials and its principal objects is to provide a receptacle wherein the contents of the can may be sprinkled therefrom or poured therefrom.

A further object of the invention is to provide a can or receptacle having a pouring outlet at one side and a sprinkler or shaker inlet at its opposite side together with valvular means for closing either the sprinkler opening or the pouring opening.

The invention also contemplates a receptacle provided with a pair of slides arranged in the guideway which may be actuated as a unit so that either one end of the can or the other may be opened.

With the preceding and other objects and advantages in mind, the invention consists in the novel combination of elements, construction and arrangement of parts and operations, to be hereinafter specifically referred to, claimed and illustrated in the accompanying drawings, wherein:—

Figure 1 is a top plan view of a receptacle constructed in accordance with my invention and showing the valves in closed position.

Figure 2 is a similar view showing the structure before the valves are associated therewith.

Figure 3 is a fragmentary sectional view of the device taken on line 3—3 of Figure 1.

Figure 4 is a transverse sectional view on line 4—4 of Figure 1.

Figure 5 is a fragmentary perspective of the guide in which the slides or valves are mounted.

Figure 6 is a perspective of one of the valves provided in the invention.

Referring to the drawings in detail wherein in corresponding characters of reference denote corresponding parts throughout the several views, the numeral 5 designates a conventional metallic can such as is used for containing spices and salt or in fact any other granular or pulverized material. The top of the can is indicated at 6 and is formed from a single sheet of metal having its edges bent and crimped around the side walls of

the receptacle as indicated at 7. This top 6 is provided with a channel shaped guide or depression which extends diagonally across the top to a point in close proximity to the corners of the receptacle. A series

of perforations 10 is provided in the channel shaped guide at one end and constitutes a shaker opening while a single relatively large opening 11 is provided in the opposite end and constitutes a pouring opening.

Struck from the side walls of the channel shaped guide or depression are pairs of transversely oppositely disposed alined clips 12 that overlie the channel shaped guides. Movable in this channel shaped guide and held against displacement therefrom is a pair of longitudinally movable slide valves 13 adapted to normally overlie the openings 10 and 11. Each of these slide valves is formed from a longitudinal strip of metal having one end bent at right angles and thence bent upon itself to provide a finger engaging element 14.

In order to lock the slide valves in position to overlie the openings 10 and 11 each of these slide valves is provided with a pair of transversely alined rounded lugs 16 which are adapted to engage the clips 12 as shown in Figure 1 of the drawings and due to the slight resiliency of these slips these lugs will pass under the same when the valves are being disposed to either an open or closed position.

As illustrated in the drawings, the finger engaging elements are so arranged as to permit both of the same to be grasped and thereby move both of the slide valves in a given direction so that the desired opening will be uncovered. It will be thus observed that the can may be used either as a sprinkler for seasoning foods or a quantity of the material may be poured therefrom.

While I have shown and described the preferred embodiment of the invention, I desire to have it understood that such changes may be made in the form, construction, arrangement of parts and operations, as will not depart from the spirit of the invention or the scope of the subjoined claim.

What is claimed is:—

The combination with a receptacle, of a channel shaped guide formed in its upper wall and provided with outlet openings at its ends, a pair of longitudinally movable slide valves seated in the channel shaped guide and normally closing the openings, transversely aligned oppositely disposed clips arranged in pairs overlying the channel shaped member, and rounded lugs

formed on each valve and cooperatively associated with said clips in such manner that the lugs of the valves engage the outer edges of the adjacent clips to casually prevent the opening of said valves when said valves are disposed in closed position and the inner edges of said clips to prevent the closing of

said valves when said valves are disposed in open position, and pass under said clips when the valves are disposed to either an 10 open or closed position.

In testimony whereof I affix my signature.

ALFRED C. HINDS.
